Application December 30, 1936, Serial No. 118,224
In Germany December 31, 1935

3 Claims. (Cl. 236—20)

My invention relates to improvements in steam generators with forced passage of the operating medium.

In generators of the above character it is well known in the art to provide the generator with an automatic control, in which the control impulses occurring in operation are derived from the changes in temperature of the operating medium contained in the preheater or superheater. By the impulses derived from these heating surface portions it is, however, not possible to attain a satisfactory control, since the impulses, depending upon whether the preheater or the superheater be employed for deriving the impulses, either arrive too soon or too late. The obvious method of deriving at a suitable moment control impulses by placing the temperature impulse receiver into the evaporation zone, located between the preheater and the superheater fails, since in this heating surface portion normally the pressure does not vary and the temperature remains constant independently of the load fluctuations. There is, however, a simple method of deriving control impulses from the zone, in which the heating surface of evaporation lies in the path of the hot gases, which method consists in providing besides the tubes forming the heating surface proper which I shall call hereinafter the main heating surface a measuring tube only traversed by liquid, heated by the same heat source as the main heating surface and particularly suitable for deriving impulses. With such a measuring tube it is possible to derive certain control impulses from any suitable point, irrespective of the manner in which it is placed in the path of the hot gases or arranged with respect to the several main heating surface portions of the boiler.

However, the use of such a measuring tube is only of particular advantage if it is possible to utilize the considerable amount of heat taken up by the measuring tube in such a manner as not to require additional expensive devices.

This may be accomplished according to the invention in a simple manner by supplying the liquid issuing from the measuring tube to the operating medium traversing the main heating surface of the boiler. To ensure in operation stable conditions of flow, it is advisable to supply the liquid issuing from the measuring tube into the path of the operating medium at a point at which only liquid flows. Consequently, the liquid is preferably supplied within the range extending from the feed point of the boiler to the

point where the preheating of the operating medium ceases.

Another question which should also be carefully considered, if by the use of a measuring tube particular advantages are to be obtained, concerns the suitable feeding of the measuring tube. In considering this question it is above all essential that the quantities of liquid passing through the tubes forming the main heating surface as well as through the measuring tube should vary in the same proportion as the load of the boiler fluctuates, if always a true picture of the processes in the main heating surface of the generator should be given by the impulse derived from the measuring tube. Also in this case it is essential that no additional expensive devices be required. This may be attained according to the invention by employing the feed pump of the boiler also for feeding the measuring tube. If the necessary conditions of flow in the measuring tube and in the main heating surface of the boiler to which the measuring tube is connected in parallel relation are not brought about by correspondingly proportioning the sectional areas of flow of the two parallel arranged parts, the desired conditions of flow may be also attained by inserting in the operating medium supply conduit of the boiler a throttle which is preferably capable of being regulated. The use of a throttle at this point permits, for instance, feeding of the measuring tube at a pressure higher than the generator inlet pressure, which will be in many cases of great importance, since there will always be a tendency to employ a comparatively narrow tube as a measuring tube so that the resistance to flow of the measuring tube may be, consequently, considerably greater than that of the main heating surface portion of the boiler to which the measuring tube is connected in parallel relation. In this case, the throttle lying in the operating medium supply conduit of the boiler must be controlled to such an extent that the measuring tube, as is required in operation, contains always liquid throughout its length. If there is danger that the ratio of the quantities flowing through the boiler and the measuring tube is disturbed by the load fluctuations of the boiler this may be under certain circumstances avoided to advantage by inserting baffle plates in the measuring tube and/or in the operating medium supply conduit of the boiler.

A practical embodiment of my invention is represented in the accompanying drawings in which similar characters of reference indicate

corresponding parts and in which Figs. 1 and 2 show the arrangement of the tubes in diagrammatic form, whereas Fig. 3 shows diagrammatically a steam generating plant embodying my invention. In the drawings 1 denotes the preheater, 2 the vaporizing heating surface, 3 the superheater. The operating medium is supplied to the boiler through the conduit 4 and the steam produced flows off through the conduit 5. 6 is the measuring tube from which the temperature impulse is derived serving to control the boiler. As will be apparent the liquid issuing from the measuring tube 6 is in all cases supplied to the operating medium contained in the main heating surface of the boiler. In the arrangement shown in Fig. 1 the liquid is supplied to the main heating surface at a point located between the preheater 1 and the evaporator heating surface 2, whereas in the arrangement according to Fig. 2 the liquid from the measuring tube is returned to the operating medium ahead of the preheater. As is indicated in Fig. 3 a throttle 7, which may have the form of a baffle plate (not shown in detail) is inserted in the liquid supply conduit 4 between the feed pump and the boiler. Instead of a baffle plate any suitable equivalent, for instance a valve may be employed as shown in Fig. 2. The conduit 4 is tapped at a point ahead of throttle 7. From this point the measuring tube 6 receives its liquid. Under certain circumstances, it is preferable to insert a valve 8 into the measuring tube in order to influence the resistance to flow prevailing in the measuring tube 6 or, if desired, to dampen the oscillations of the liquid. The boiler is heated by a burner 9 which is fed with fuel through a conduit 10 by a pump 11. 12 is the driving motor for the pump 11. The speed of the motor 12 may be regulated by the switch rheostat 13 whose switch 14 may be rotated by an electric motor 15. This motor may be rotated in the one or the other direction depending upon which of the two relays 16 or 17 is operated. 18 and 19 indicate points at which the temperature is measured. In the arrangement shown in Fig. 3 thermo-elements are employed which may be inserted, for instance, in series in one branch of a Wheatstone bridge 20. In the diagonal conductor 21 of the bridge is inserted a measuring instrument 22 of a suitable type whose pointer connects the conductor 23 for energizing the rheostat coils 16 or 17 with the conductor 24 or 25 depending upon the manner in which the balance of the bridge is disturbed owing to the changes in temperature measured at the points 18 and/or 19. Accordingly either the relay 16 or the relay 17 is energized and operates the speed regulator for the motor 12 driving the pump 11 in the desired direction. The operating conditions are so chosen that upon an increase in temperature at the points 18 and/or 19 the fuel supply from the pump 11 is reduced by lowering the pump speed and vice versa. The water is supplied by a pump 26 driven by a motor 27.

I claim as my invention;

1. In a forced flow tubular steam generator having a liquid operating medium supply and a fuel supply for heating its furnace, a measuring tube traversed throughout only by a liquid medium similar to the generator medium, and disposed adjacent to and along at least a portion of the main tubular heating surface, so that its length in the furnace is exposed simultaneously and jointly with the main tubular heating surface to the temperatures of the furnace heat zones, and means for controlling the fuel supply in accordance with the temperature variations prevailing at the entrance of said measuring tube into and its exit from the furnace, and means for supplying the liquid issuing from said measuring tube into the medium flow path of said generator at a point at which the operating medium is still in a liquid state. 5

2. In a forced flow tubular steam generator having a liquid operating medium supply and a fuel supply for heating its furnace, a measuring tube traversed throughout only by a liquid medium similar to the generator medium, and connected for its medium supply to said operating medium supply, and disposed adjacent to and along at least a portion of the main tubular heating surface, so that its length in the furnace is exposed simultaneously and jointly with the main tubular heating surface to the temperatures of the furnace heat zones, and means for controlling the fuel supply in accordance with the temperature variations prevailing at the entrance of said measuring tube into and its exit from the furnace, and means for supplying the liquid issuing from said measuring tube into the medium flow path of said generator at a point at which the operating medium is still in a liquid state. 20

3. In a forced flow tubular steam generator having a liquid operating medium supply and a fuel supply for heating its furnace, a measuring tube traversed throughout only by a liquid medium similar to the generator medium, and connected for its medium supply to said operating medium supply, and disposed adjacent to and along at least a portion of the main tubular heating surface, so that its length in the furnace is exposed simultaneously and jointly with the main tubular heating surface to the temperatures of the furnace heat zones, and means for controlling the fuel supply in accordance with the temperature variations prevailing at the entrance of said measuring tube into and its exit from the furnace, and means for supplying the liquid issuing from said measuring tube into the medium flow path of said generator at a point at which the operating medium is still in a liquid state. 25

4. In a forced flow tubular steam generator having a liquid operating medium supply and a fuel supply for heating its furnace, a measuring tube traversed throughout only by a liquid medium similar to the generator medium, and connected for its medium supply to said operating medium supply, and disposed adjacent to and along at least a portion of the main tubular heating surface, so that its length in the furnace is exposed simultaneously and jointly with the main tubular heating surface to the temperatures of the furnace heat zones, and means for controlling the fuel supply in accordance with the temperature variations prevailing at the entrance of said measuring tube into and its exit from the furnace, and means for supplying the liquid issuing from said measuring tube into the medium flow path of said generator at a point at which the operating medium is still in a liquid state. 30

5. In a forced flow tubular steam generator having a liquid operating medium supply and a fuel supply for heating its furnace, a measuring tube traversed throughout only by a liquid medium similar to the generator medium, and connected for its medium supply to said operating medium supply, and disposed adjacent to and along at least a portion of the main tubular heating surface, so that its length in the furnace is exposed simultaneously and jointly with the main tubular heating surface to the temperatures of the furnace heat zones, and means for controlling the fuel supply in accordance with the temperature variations prevailing at the entrance of said measuring tube into and its exit from the furnace, and means for supplying the liquid issuing from said measuring tube into the medium flow path of said generator at a point at which the operating medium is still in a liquid state. 35

6. In a forced flow tubular steam generator having a liquid operating medium supply and a fuel supply for heating its furnace, a measuring tube traversed throughout only by a liquid medium similar to the generator medium, and connected for its medium supply to said operating medium supply, and disposed adjacent to and along at least a portion of the main tubular heating surface, so that its length in the furnace is exposed simultaneously and jointly with the main tubular heating surface to the temperatures of the furnace heat zones, and means for controlling the fuel supply in accordance with the temperature variations prevailing at the entrance of said measuring tube into and its exit from the furnace, and means for supplying the liquid issuing from said measuring tube into the medium flow path of said generator at a point at which the operating medium is still in a liquid state. 40

7. In a forced flow tubular steam generator having a liquid operating medium supply and a fuel supply for heating its furnace, a measuring tube traversed throughout only by a liquid medium similar to the generator medium, and connected for its medium supply to said operating medium supply, and disposed adjacent to and along at least a portion of the main tubular heating surface, so that its length in the furnace is exposed simultaneously and jointly with the main tubular heating surface to the temperatures of the furnace heat zones, and means for controlling the fuel supply in accordance with the temperature variations prevailing at the entrance of said measuring tube into and its exit from the furnace, and means for supplying the liquid issuing from said measuring tube into the medium flow path of said generator at a point at which the operating medium is still in a liquid state. 45

8. In a forced flow tubular steam generator having a liquid operating medium supply and a fuel supply for heating its furnace, a measuring tube traversed throughout only by a liquid medium similar to the generator medium, and connected for its medium supply to said operating medium supply, and disposed adjacent to and along at least a portion of the main tubular heating surface, so that its length in the furnace is exposed simultaneously and jointly with the main tubular heating surface to the temperatures of the furnace heat zones, and means for controlling the fuel supply in accordance with the temperature variations prevailing at the entrance of said measuring tube into and its exit from the furnace, and means for supplying the liquid issuing from said measuring tube into the medium flow path of said generator at a point at which the operating medium is still in a liquid state, and a flow resistance between said tubular generator and its operating medium supply, whereby said measuring tube is fed from said operating medium supply at a pressure higher than the pressure at which the medium flows into the generator. 50
